UNITED STATES PATENT OFFICE

CHARLES A. BROWNE, OF BROCKTON, MASSACHUSETTS, ASSIGNOR OF ONE-HALF TO
CHARLES H. BEANE, OF CAMBRIDGE, MASSACHUSETTS

SCREEN DEVICE

Application filed May 9, 1932. Serial No. 610,029.

This invention relates to a screen device.

One object of my invention is to make screens more adaptable and convenient for every day occasions and needs. Another object is to make a screen which will close sufficiently tight and yet may be used in window openings of different widths. Still another object is to provide a screen device which enables the screen to be pushed outwardly or slid up or down. A further object is to make such a screen and device so simple that the operation will be readily understood and the cost will be approximately that of an ordinary screen.

15 The foregoing and other objects will appear as the nature of the invention is better understood, may be accomplished by a construction, combination and operative arrangement of parts such as is disclosed by the drawing. The nature of the invention is such as to render it susceptible to various changes and modifications, and, therefore, I am not to be limited to the construction disclosed by the drawing, but am entitled to all 20 such changes therefrom as fall within the scope of my claims.

In the drawing:

Figure 1 is a front elevation of a window with my screen in closed position.

30 Figure 2 is a cross-section on line 2-2 of Figure 1, showing the screen swung outwardly.

Figure 3 is a cross-section showing a fixture in position which serves as a pivot holder and guide for the screen, and a combination raising and locking member in locking position.

40 Figure 4 is a perspective of my pivoting and guide fixture.

Figure 5 is a perspective view of a spring washer for said screen fixture.

Figure 6 is an enlarged fragmentary perspective showing the corner construction on the inside of my screen.

45 As illustrated, my invention is used in connection with the outer frame 12 in a building which is adapted to receive a window 13 therein, and a screen 14, which screen comprises wire screening 15, frame pieces 16 joined together and reinforced at the corners

by a metal strap 17. This metal strap 17 is made of the same piece of metal that extends around the full length of each side of said screen as shown at 19, and which continues to also form a flange 18 on each side of the screen, which flanges 18 extend beyond the screen frame and rest against or close to said outer frame 12 when the screen is in closed position. It will thus be seen that the screen need not be made of such a size that it is a good fit, as to width, for the window opening, as said flanges 18 makes it sufficiently tight against said outer frame 12 anyway, and a loose inside fit is desirable so that it may be swung outwardly without binding. As thus made said screen 14 costs practically the same as the ordinary window screen; but is much more serviceable as will be seen.

To make said screen 14 movable outwardly by merely pushing it and also movable upwardly, I provide a fixture 20 having a hole 21 in a flat portion therein through which a screw or pin 26, later described, passes. Said fixture 20 is formed so as to provide a guide-way 22 therein at the front and extending laterally in which said flange 18 may slide. In fastening said fixture 20 to the window frame or casement I preferably use a spring metal washer 24 having a hole 25 therein, and this washer 24 rests against said outer frame 12 and the fixture 20 rests against said washer 24 with said screw 26 passing therethrough and entering said outer frame 12, as best illustrated in Figure 3 of the drawing. Said fixture 20 is pivotally held by said screw 26 so the screen may readily be pushed outwardly. Said spring washer 24 presses tightly against said fixture 20 and will hold said screen in any outward position it is moved to, yet its spring qualities enable it to yield so that a person may push said screen outwardly or pull it inwardly with a moderate amount of strength. It is, of course, possible to dispense with said washer 24, if it is not desired to provide for said screen remaining in an open position.

I also provide for convenience and at very little expense a spring member 28 which is a combination locking device and finger grip. I preferably use with it a spring washer 29

which rests against said screen 14, and a screw 30 which serves as a pivot, passes through said locking member 28 and said washer 29 and screws into said screen 14, so that a portion of said member 28 may be moved against said outer frame 12 as shown in Figure 3 of the drawing, thereby locking the screen in place, and this same locking portion also serves as a finger hold or grip by which the screen may be conveniently raised, and after raising to any desired position it may be held there by moving said locking portion against said outer frame as described, the force of said spring member 15 against said outer frame holding said screen in any position it is raised to.

To prevent said screen 14 from sliding out of the guideways 22 when it is pushed outwardly, I preferably provide a stop pin or screw 32 at the top thereof on each side, which projects outwardly so that it will contact with said fixture 20 and thereby prevent the screen from sliding downwardly.

What I claim is:

1. A screen device comprising a screen embodying a flange on each side, and a plurality of fixtures adapted to be pivotally fastened to a window opening frame and having provision for said flanges to slide therein.

2. A screen device comprising a screen having a member on each side thereof extending beyond the body of said screen, and a plurality of fixtures adapted to be pivotally fastened to a window opening frame, and having guideways therein at the front thereof in which said members are adapted to slide.

3. A screen device comprising a screen having a flange extending beyond each side thereof, and a plurality of fixtures adapted to be pivotally fastened to a window opening frame and each provided with laterally extending guideways in which said flanges may slide, and means to prevent said flanges sliding downwardly out of said guideways.

4. A screen device comprising a screen having a flange on each side thereof extending laterally beyond the body of and adjacent the outer surface of said screen, and a plurality of fixtures, each embodying a flat portion adapted to be fastened to a window opening frame and another portion at approximately right angles to said first-mentioned portion formed, to provide a guideway extending laterally and having an open mouth portion at the left thereof when in position, and means at the upper portion of said screen to prevent said flanges sliding downwardly out of said guideways.

5. A screen device comprising a screen having a flange on each side thereof extending laterally beyond the body of said screen, and a plurality of fixtures each embodying a flat portion having a hole therein adapted to be fastened to a window opening frame and

another portion at approximately right angles to said flat portion having a guideway therein extending laterally and having an open mouth portion, the part forming said guideway at the front extending beyond said flat portion at both the right and left, and means at the upper portion of said screen which is adapted to contact with said fixtures to thereby prevent said flanges sliding downwardly out of said guideways.

6. A screen device comprising a screen embodying a flange on each side, and a plurality of fixtures adapted to be pivotally fastened to a window opening frame and spring means for said fixtures, said fixtures having provision for said flanges to slide therein.

7. A screen device comprising a screen having a flange on each side thereof extending beyond the body of said screen, fixtures adapted to be pivotally fastened to a window opening frame, and spring means adapted to exert pressure on said fixtures, said fixtures having guideways therein in which said flanges slidably fit, and means to prevent said flanges sliding downwardly out of said guideways.

8. A screen device, comprising a screen having a flange on each side thereof extending beyond the body of said screen adapted to overlap a portion of a window opening frame, a fixture pivotally fastened to said frame, a spring washer in contact with said frame and said fixture and exerting pressure on said fixture, said fixtures having guideways therein in which said flanges slidably fit, and means to prevent said flanges sliding downwardly out of said guideways.

9. A screen device, comprising a screen having a flange on each side thereof extending beyond the body of said screen and adapted to overlap a portion of a window opening frame, a fixture adapted to be pivotally fastened to said frame, a spring washer adapted to contact with said frame and said fixture and exert pressure on said fixture, said fixture having a portion extending outwardly at the front of and adapted to extend beyond said frame and forming a guideway in which said flange slidably fits, and means to prevent said flange sliding downwardly out of said guideway.

10. A screen device, comprising a screen having a flange on each side thereof extending outwardly beyond the body of said screen, a plurality of fixtures adapted to be fastened to a window frame in such a manner as to be movable, said fixtures having guideways therein in which said flanges slidably fit, and a member movably fastened to said screen adapted to be moved into contact with said frame to thereby prevent any outward movement of said screen, and means to prevent said flanges sliding downwardly out of said guideway.

11. A screen device, comprising a screen

having a flange on each side thereof extending outwardly beyond the body of said screen, a plurality of fixtures adapted to be movably fastened to a window frame, each of said fixtures having a guideway therein in which a said flange slidably fits, a member movably fastened to said screen adapted to be moved to a position in which a portion is beyond the outside edge of said screen, spring means adapted to exert pressure upon said member to thereby force it against said frame, and means to prevent said flanges sliding downwardly out of said guideways.

12. A screen embodying wire screening, frame pieces surrounding said screening, and a single piece of metal forming a metal strap extending across the joint between one frame piece and another and also forming a flange at the side of said screen extending beyond the adjoining said frame piece.

13. A screen device comprising a screen embodying a single piece of metal at each side thereof which extends from the frame portion of said screen outwardly to form a flange at the side of said screen, a plurality of fixtures each embodying a flat portion having a hole therein for pivotally holding said fixtures to a window opening frame, said fixtures also embodying another portion extending outwardly and forming a guideway in which said flange is slidably mounted, and means to prevent said flanges sliding downwardly out of said guideways.
